(57) CLAIM

We claim the ornamental design for a taco rack, as shown and described.

DESCRIPTION

FIG. 1 is a front, top and side perspective view of the taco rack embodying the design of the present invention.

FIG. 2 is a front elevational view thereof.

FIG. 3 is a rear elevational view thereof.

FIG. 4 is a side elevational view thereof.

FIG. 5 is a side elevational view thereof of the side opposite to the side shown in FIG. 4.

FIG. 6 is a top plan view thereof; and,

FIG. 7 is a bottom plan view thereof.
